ABSTRACT OF THE DISCLOSURE

A device for chilling drinking glasses, the device including a mechanism for delivering carbon dioxide under pressure through a condensing coil within a cooling box which is then delivered to the inner surface of a wet drinking glass.

This invention relates generally to cooling devices. More specifically, it relates to devices for chilling glassware.

It is generally well known that many beverages and liquors are preferred to be served from glassware that is chilled, thereby accentuating the freshness of the drink. Thus, various methods have been devised for pre-chilling said glassware for this purpose.

The principal object of the present invention is to provide a drinking glass chiller device which will chill glasses to a lower temperature than is possible by conventional methods presently being employed.

Another object of the present invention is to provide a drinking glass chiller device which incorporates the blast of a carbon dioxide gas through a condensing coil within a cooling box and to the inner surface of a wet drinking glass.

Another object of the present invention is to provide a drinking glass chiller device which can be readily incorporated for use in a commercial bar as well as for a bar at home.

Yet another object is to provide a drinking glass chiller device which is economical.

Other objects of the present invention are to provide a drinking glass chiller device which is simple in design, inexpensive to manufacture, rugged in construction, easy to use and efficient in operation.

These and other objects will be readily evident upon a study of the following specification and the accompanying drawing wherein:

FIGURE 1 is a perspective view of the present invention shown partly in cross section and,

FIGURE 2 is a side elevation view thereof shown installed upon a bar.

Referring now to the drawing in detail, the reference numeral 10 represents a drinking glass chiller device according to the present invention wherein there is a housing 11 enclosing a central compartment 12 within which there is a mechanism 13 that is used for chilling a drinking glass 14 that is placed thereupon.

The mechanism 13 includes a platform 15 that is located adjacent a central opening 16 upon the upper wall 17 of the housing 11. The opening is provided for placement of the inverted drinking glass 14 thereinto. The platform is supported upon a plurality of bolts 18 each of which has a compression coil spring 19 fitted there around, the coil springs normally urging the platform

2

15 upwardly against the underside of the top wall 17. The bolts 18 are mounted upon brackets 20, one of the brackets 20 also supporting a micro-switch 21, having an actuating arm 22 that projects upwardly towards the underside of the platform 15.

A central opening 23 within the platform 15 is concentric with central opening 16, the opening 23 providing a clearance for a jet nozzle 24 projecting upwardly from a solenoid valve 25. At its lower end, the solenoid valve 25 is connected by a pipe 26 which is connected at its opposite end to a condensing coil 27. As shown in FIGURE 2 of the drawing, the condensing coil is located externally of the housing 11.

A light bulb 28 is mounted upon a lamp socket 29 secured to a bracket 20, the light bulb providing visual indication means when the device is in operation.

The housing 11 is mounted upon a base 30 and is secured thereto by means of a retaining band 31 having a snap hook 32. A toggle switch 33 is mounted upon the base 30, and the base further provides a means for an electric cord 34 to protrude therethrough, the cord 34 having a conventional electric plug 35 at its outward end. Likewise, the pipe 26 protrudes sidewardly out of the base, the terminal end thereof being threaded as shown at 36 for purpose of threadingly engaging with the condensing coil.

The drinking glass chiller device 10 may be suitably positioned upon a counter 37 of a bar as shown in FIGURE 2 of the drawing, where the pipe 26 is connected to the lowermost turn of coil 27, the uppermost turn of the coil 27 being connected to a conventional storage tank cylinder 38 containing carbon dioxide under pressure. The cylinder 38 may be located out of the way below a sink 39 or other unobtrusive place.

In operative use, a drinking glass 14 is first wet upon the inner side with water and is then positioned in an inverted manner as shown within the opening 16, the rim of the glass resting against the upper side of platform 15. The operator then pushes downwardly upon the glass, thus causing the platform 15 to descend against the operating arm of the micro-switch which thus causes an electrical circuit to be closed which activates the solenoid valve 25 and which further lights up the lightbulb 28. When the solenoid valve is opened, it releases carbon dioxide through the jet nozzle 24 against the inner surface of the drinking glass. The light bulb shows the progress of the glass being frosted, in view that the platform 15 is made of a plastic panel which may be transparent for this purpose. The glass will become frosted within several seconds after which the glass is raised upwardly thus closing the electric circuit again. In this operation, the condensing coil 27 located within a cooling box 40, lowers the carbon dioxide temperature and condenses the carbon dioxide vapor into carbon dioxide liquid, which is needed for the glass chilling operation.

It is to be noted that the chilling unit can also be hooked to a syphon type carbon dioxide tank if so preferred.

While various changes may be made in the detailed construction, it is understood that such changes will be within the spirit and scope of the present invention as is defined by the appending claims.

What I now claim is:

1. A glass chilling device comprising a source of pressurized refrigerant, a light transparent platform means

adapted for receiving an inverted glass on the top side thereof, platform mounting means on the underside of the platform which allow for reciprocable movement of the platform, refrigerant nozzle means mounted in the platform, means connecting the source of refrigerant to the nozzle means, a light source mounted underneath the platform and means actuated by the downward movement of the platform to discharge the refrigerant onto the glass to thereby produce a frosted glass, said light source illuminating the glass through the platform to thereby give visual indication of the amount of frost formed thereon.

2. The device of claim 1 wherein the light source is actuated with the downward movement of the platform and coincident with the discharge of refrigerant.

3. The device of claim 1 wherein the source of pres-

surized refrigerant is a pressure cylinder of carbon dioxide.

4. The device of claim 1 in which the platform is made of transparent plastic.
